UNITED STATES PATENT OFFICE.

HENNING FRIEDRICH WALLMANN, OF CHICAGO, ILLINOIS, ASSIGNOR OF ONE-HALF TO
ADELHEID WALLMANN, WILHELM ROGER WALLMANN, AND HENNING HEINRICH
WALLMANN, ALL OF CHICAGO, ILLINOIS.

GAS-PRODUCER.

1,125,919.

Specification of Letters Patent. Patented Jan. 19, 1915.

Application filed July 20, 1908. Serial No. 444,517.

To all whom it may concern:

Be it known that I, HENNING FRIEDRICH WALLMANN, a citizen of the United States, residing at Chicago, in the county of Cook and State of Illinois, have invented a new, useful, and Improved Gas-Producer, of which the following is a full, clear, and exact description, reference being had to the accompanying drawings, forming a part of 5 this specification, in which similar letters and numerals of reference in the different figures indicate like parts.

My invention relates to gas producers and more particularly to a type of gas producer 15 in which hydrocarbonaceous fuel, such as bituminous coal, lignite, peat, wood, straw, cornstalks, etc., is gasified in three stages, consisting, first, in imperfectly and primarily distilling the freshly supplied fuel 20 by conduction and convection of heat, preferably of heat from hot gaseous products generated by partial combustion of carbon in the second and third stage of the gasifying process, and, preferably, by means of 25 superheated steam; second, in oxidizing a part of the carbon of the resulting residue of imperfect, primary distillation by a first supply of free oxygen; in perfectly and secondarily distilling said residue by means of 30 the resulting heat; and in converting also by means of this heat condensable distillates generated by this secondary distillation, into permanent, fixed gas; and third, in oxidizing the remaining carbon or coke by a sec- 35 ond supply of free oxygen to carbon-monoxid; in converting by means of the resulting heat, condensable distillates, generated by primary, imperfect distillation of freshly supplied fuel, into permanent, fixed gas; and 40 in disassociating also by means of this heat steam into its chemical elements, hydrogen and oxygen, of which the latter engages with carbon to carbon-monoxid; and the object of 45 my improvements is to simplify the construction of an apparatus which is adapted for a continuous process of gasifying hydro- 50 carbonaceous fuel in the said three stages and which may be constructed as well in comparatively small dimensions as in larger 55 dimensions fit for the production of the greatest quantities of gas manufactured.

The construction of the apparatus is based on the experience that in order to penetrate a quantity of fuel by heat, and preferably

by steam for its distillation and by air for 55 its partial combustion, it is of great advantage to put the fuel into comparatively narrow conduits into which and through which the fuel is preferably transported for and during its gasifying process respectively 60 with the assistance of mechanical means.

If a quantity of bituminous coal is heated, it bakes, clogs, increases in volume and considerably impedes a penetration by air, steam and also by vapors and distillates 65 generated in its interior. However there is this difference: it consumes power of a motor to force air through baking coal, whereas heat, evaporating water and volatile constituents of coal, simultaneously may also 70 create the pressure required for the steam, vapors and distillates to penetrate the residue of coal from which these vapors and distillates are separated. As the presence of superheated steam greatly facilitates the 75 evaporation of volatile constituents of fuel, a considerable portion of these constituents may within a short time be separated from the residue which thereby becomes porous and now may easily be penetrated by a cur- 80 rent of air, the oxygen of which burns with a portion of the carbon to carbon-monoxid and evaporates by the generated heat the rest of the volatile constituents yet con- 85 tained in the residue of primary distilla- 85 tion and converts also the condensable dis- 90 tillates of this secondary distillation into permanent gases, whereas the condensable distillates of the primary distillation are destroyed by heat generated by a second 95 current of air passing through and burning residue of secondary distillation to carbon- monoxid, simultaneously disassociating the steam used for the primary distillation into its chemical elements, thereby generating 95 hydrogen and carbon-monoxid.

In order to facilitate the promotion of the described process, I change the usual form of the ground-plan of gas producers which usual form is circular, into an oblong 100 ground-plan which according to the amount of fuel that is to be gasified during a certain period, may be several times as long as it is wide, and I adapt the rest of the construction of my gas-producer, especially the 105 means for introducing the fuel and for removing the ashes to this oblong ground- plan. The means for introducing the fuel

are also modified according to the nature of the special fuel used.

In the drawings: Figure 1 shows a vertical cross-section illustrating the general principle of my gas-producer. Fig. 2 is a vertical longitudinal section at right angles to Fig. 1, parts being broken off. Fig. 3 is a vertical cross-section at reduced scale of the lower part of a modified gas-producer.

10 P is the producer shaft, D the distillation conduit and M a magazine for fuel.

In the case that no steam is introduced into the distillation conduit D and used for distilling the fuel, the construction of the

15 gas producer may be symmetrical on both sides of the vertical center line of Fig. 1.

For the sake of greater clearness the right side of Fig. 1 represents a section through a canal 20 leading the generated hot gases

20 from the producer shaft P toward the distillation conduit D for heating the fuel therein, whereas the left side of Fig. 1 represents a section through a canal 25 leading distillates from the distillation conduit D

25 into the lower part of the producer shaft P. From Fig. 2 it will be observed that between

every two canals 20, used for the transport of hot gases, a canal 25^a is arranged which may be used for the transport of distillates

30 through the canal 26 and its distributing holes 28 into the lower part of the producer shaft P on the right side of Fig. 1, just in the same way as the canal 25 is employed on

35 the left side of Fig. 1. But the upper parts of these canals 25^a on the right side of Fig. 1 may preferably, in conjunction with the steam supply pipe 36, the distributing tubes

37 and the distributing holes 24^a, be employed for introducing steam, preferably su-

40 perheated steam into the distillation conduit D. In this case the lower part of the canals 25^a and the canal 26 with its distributing holes 28 may be left out as is indicated in

Fig. 3.

45 The fire-proof lined producer shaft P in Figs. 1 and 2, is provided with a grate 11 and with suitable ports for the removal of the ashes and clinkers. Air may be introduced into the lower part of the producer

50 shaft P through the pipe 12, the ash pit and grate 11. Air may also be introduced into the upper part of the producer shaft P through the pipe 13, the parallel canals 14 and 15 and the air inlets 16. The generated

55 gas is withdrawn through the gas outlets 17 entering into the parallel canals 18 and 19 from where the gas may flow through canals

20 toward the distillation conduit D having metal walls and being situated on top of the

60 producer shaft P. The gas, after imparting its sensible heat through the metal walls of the distillation conduit D to the fuel contained therein, flows into parallel canals 21 and 22 and from there into the gas discharge

65 pipe 23. The distillates evaporated within

the distillation conduit D enter through perforations 24 and eventually 24^a into canals 25 and 25^a respectively and from there into parallel canals 27 and 26 respectively, communicating through inlets for distillates 28 with the lower part of the producer shaft P. Said inlets for distillates 28 lead preferably into the fuel bed of the up-draft combustion-zone within the producer shaft P and are preferably located below the gas outlets 17 and above a lower air-inlet or above lower air-inlets, it being assumed in the drawing that the lower air-inlets into the fuel-bed of the producer shaft P are formed by the interstices between the grate-bars of the grate 11. The distance between the inlets for distillates 28 and the lower air-inlets (between the grate-bars) may be so great that the free oxygen of the entering air is combined with carbon in proximity to the grate 11 and is thus prevented from coming in its free state into contact with distillates entering from the inlets 28, and from consuming hydrogen contained in these distillates. It will be remembered that if hydro-carbons 90 come into contact under proper temperature with a limited amount of air, the hydrogen contained in the hydro-carbons burns first in preference of the carbon which may become disengaged in the form of smoke, soot or 95 lamp black. In order to produce from hydro-carbonaceous fuel a gas of greatest possible heat-value, the hydrogen contained in the hydro-carbon of the fuel should not be consumed, but, if a tarless gas is required. 100 with the condensable distillates converted into permanent, fixed gases, these distillates should be heated and thereby decomposed in the absence of free oxygen and only to such degree as is unavoidable for producing a 105 certain quality of gas. Carbon-dioxid or carbon-monoxid resulting from the combustion of carbon by air, do not consume hydrogen, but carbon-dioxid may combine to carbon-monoxid with carbon disengaged from 110 heated condensable hydro-carbons in converting the latter into a permanent, fixed gas. By distilling hydro-carbonaceous fuel in the absence of free oxygen, by burning the resulting coke or charcoal, by mixing 115 the resulting hot products of combustion with the generated distillates and a regulated amount of steam under a thereby regulated temperature, and by transferring the sensible or perceptible heat of the finally resulting gas-mixture gradually by conduction to the freshly supplied hydro-carbonaceous fuel under distillation and eventually to the required water and air, a tarless gas of maximum heat-value will be generated from 125 a specific kind of hydro-carbonaceous fuel. The arrangement illustrated produces thus a tarless gas of much higher heat-value from a certain kind of fuel than can be generated with a combustion by air of generated dis- 130

tillates or of hydrogen contained in the hydro-carbons thereof, as is done in numerous existing gas producers. Non-conductors of heat may protect the canals 20, 25 and 25^a against considerable loss of heat by conduction and radiation.

The fuel is introduced through hoppers 29 into the magazine M from where it falls by its gravity into the distillation conduit D, the cross area of which increases in the direction toward the producer shaft P below. Mechanical pushers 30, 30, reciprocating in vertical direction slowly push the coal down from the distillation conduit D into the producer shaft P below, and increase the tendency of the coal to gradually move down to the grate 11. The reciprocating motion of the mechanical pushers 30, 30, may be effected in any well known suitable way either intermittently and by hand-power or continuously by the power of an engine or motor. The distillates entering through the inlets 28 also protect the fire-proof lining of the lower part of the producer shaft P against too great heat.

In case that there is an opportunity for manufacturing valuable tar products and ammonia from the distillates of primary distillation, or in the case that a mixture of these distillates with steam is to be used for manufacturing a water gas of high heat value, these distillates or their mixture with steam may be withdrawn through tubes 38 and a collecting pipe 39 in any suitable way from the canals 25 and may be carried to any desirable location instead of being led into the lower part of the producer shaft P. In the modification shown in Fig. 3, air is introduced through a canal 31 and through air distributing holes 32 similarly arranged as the air distributing holes 16 in Figs. 1 and 2. The ashes are removed from the producer shaft P, into the ash pit 35 by means of a rotary drum 33 having outside flanges 34 in the direction of radii.

The apparatus operates as follows: In order to start the operation, a fire is kindled on the grate 11 or on top of the drum 33, and a moderate air draft is produced in any suitable way. As soon as the fire is sufficiently developed, the air current may be reinforced by sucking the products of combustion by means of a fan or ventilator, (as is in common use in gas producers), out of the pipe 23 and by discharging the same into the atmosphere. The producer shaft and preferably the lower part of the distillation conduit D are then filled with coke or anthracite coal and the rest of the distillation conduit D and the magazine M with bituminous coal, whereupon gas will be generated as soon as the whole mass of fuel within the producer shaft and in the distillation conduit is sufficiently hot.

Steam may then be raised in any suitable

way and be either mixed with the air which is used for the combustion, or preferably may be introduced into the distillation conduit. The gas may then be cleaned in scrubbers and be stored in gas holders as is usual in gas producers.

What I claim as my invention and desire to secure by Letters Patent is:

1. In a gas producer, a down-draft gas generating chamber surrounded by a wall of refractory material, an air-inlet into the upper part of said chamber, a gas outlet from said chamber and below said air inlet, a conduit partly inclosed by a metal wall and located anterior of said chamber, an inlet for solid fuel into said conduit, an outlet for heated solid fuel from said conduit past said air inlet into said chamber, a gas discharge canal from said gas outlet and extending past said conduit, and said metal wall constructed to keep apart from each other but to be in contact with gas in said canal and solid fuel in said conduit for transferring heat from said gas to said fuel.

2. In a gas producer, a producer shaft, an upper and a lower air-inlet into and an intermediate gas outlet out of said producer shaft, a distillation conduit anterior of said producer shaft, an inlet for solid fuel into said conduit, an outlet for residue of distillation from said conduit past said air-inlet into said producer shaft, means for heating said conduit and fuel therein, a separate outlet for distillates from said conduit, an inlet for distillates into said producer shaft and located between said upper and said lower air-inlet, a canal connecting said outlet for distillates and said inlet for the same, and a wall above said inlet for distillates and constructed so as to prevent said distillates coming in contact with and being consumed by a consequential amount of free oxygen from the atmosphere in their passing from said inlet for distillates through the fuel-bed in said producer shaft toward said gas outlet.

3. In a gas producer, a combustion chamber, a distillation conduit, an inner and an outer metal wall connected one to the other and partly inclosing said conduit, two compartments between said walls, a partition separating the said two compartments from each other, an inlet for leading hot gases from the said chamber into one of said two compartments, and an aperture in the said inner wall and connecting the said conduit to the other of the said two compartments.

4. In a gas producer, a distillation conduit with perforated side wall for distilling fuel, a combustion chamber, a canal with wall partly integral with said side wall for heating fuel in said conduit and for discharging gaseous products from said chamber, a canal for leading steam through said perforated side wall into said conduit, and a

canal for discharging a mixture of steam and distillates from said conduit.

5. In a gas producer, a distillation conduit with perforated walls for distilling fuel, a combustion chamber, a plurality of canals with walls partly integral with said perforated walls for heating fuel in said conduit and for discharging gaseous products from said chamber, a plurality of canals for 10 leading steam through said perforated walls into said conduit, and a canal for discharging a mixture of steam and distillates from said conduit.

6. In a gas producer, a down-draft combustion chamber, an air-inlet into the upper part of said chamber, a plurality of gas outlets from the lower part of said chamber and below said air-inlet, a distillation conduit anterior of said chamber and provided with an inlet for solid fuel and constructed to supply such fuel toward and into the upper part of said chamber and past said air-inlet, and a plurality of gas discharge canals from said gas outlets and 20 extending past said conduit and each partly inclosed by a heat conducting wall constructed to be in contact on one of two opposite sides thereof with hot gaseous contents discharged through one of said outlets and on 25 the other of said sides with solid fuel in said conduit, but to keep separate said gaseous contents from said fuel.

7. In a gas producer, a producer shaft comprising a down-draft combustion chamber, an air-inlet into the upper part of said chamber, a plurality of gas-outlets from the lower part of said chamber and below said air-inlet, a distillation conduit anterior of said chamber and provided with an inlet for solid fuel and constructed to supply such fuel toward and into the upper part of said chamber and past said air-inlet, a plurality of gas discharge canals from said gas outlets and extending past said conduit 40 and each partly inclosed by a heat conducting wall constructed to be in contact on one of two opposite sides thereof with hot gaseous contents discharged through one of said outlets and on the other of said sides 45 with solid fuel in said conduit, but to keep separate said gaseous contents from said fuel, an inlet for distillates into said producer shaft, and a canal for distillates communicating through a perforated wall with 50 said conduit and through said inlet for distillates with said producershaft.

8. In a gas producer, a down-draft combustion chamber, an air-inlet into the upper part of said chamber, a plurality of gas outlets from said chamber and below said air-inlet, a distillation conduit anterior of said chamber and provided with an inlet for solid fuel and constructed to supply such fuel toward and into the upper part of said chamber, an inlet for fluid not containing

a consequential amount of free oxygen into said conduit, and a plurality of gas discharge-canals from said gas outlets and extending past said conduit and each partly inclosed by a heat conducting wall constructed to be in contact on one of two opposite sides thereof with hot gaseous contents discharged through one of said outlets and on the other of said sides with solid fuel in said conduit, but to keep separate said gaseous contents from said fuel. 70

9. In a gas-producer, a distillation-conduit, two perforated walls on opposite sides of the said distillation-conduit, two canals in communication through the said perforated walls with the said distillation-conduit and through this conduit with each other, one of the said two canals for leading a hot fluid not containing a consequential quantity of free oxygen through one of the 80 said two perforated walls into the said distillation-conduit, and the other of the said two canals for discharging the said fluid mixed with distillates from the other of the 85 said two perforated walls. 90

10. In a gas producer, a producershaft comprising a down-draft combustion chamber, an air-inlet into the upper part of said chamber, a plurality of gas outlets from said chamber, and below said air-inlet, a distillation conduit anterior of said chamber and provided with an inlet for solid fuel and constructed to supply such fuel toward and into the upper part of said chamber, an inlet for fluid not containing a consequential amount of free oxygen into said conduit, a plurality of gas discharge canals from said gas outlets and extending past said conduit and each partly inclosed by a heat conducting wall constructed to be in contact on one 100 of two opposite sides thereof with hot gaseous contents discharged through one of said outlets and on the other of said sides with solid fuel in said conduit, but to keep separate said gaseous contents from said fuel, an inlet for distillates into said producershaft, and a canal for distillates communicating through a perforated wall with 110 said conduit and through said inlet for distillates with said producershaft. 110

11. In a gas producer, a distillation conduit with perforated walls for distilling fuel, a combustion chamber, a canal with wall partly integral with one of said perforated walls for heating fuel in said conduit and for discharging gaseous products from said chamber, a canal for leading a fluid not containing a consequential amount of free oxygen through one of said perforated walls into said conduit, and a canal for 120 discharging a mixture of said fluid and distillates through another of said perforated walls from said conduits. 120

12. In a gas producer, a producershaft, a lower and an upper air-inlet into and a 130

- plurality of intermediate gas outlets out of said producershaft, a distillation conduit provided with an inlet for solid fuel and constructed to supply such fuel toward and into the upper part of said producershaft past said upper air-inlet, and a plurality of gas discharge canals on substantially opposite sides of said producershaft from said gas outlets and extending past said conduit and each partly inclosed by a heat conducting wall constructed to be in contact on one of two opposite sides thereof with hot gaseous contents discharged through one of said outlets and on the other of said sides with solid fuel in said conduit, but to keep separate said gaseous contents from said fuel.
13. In a gas producer, an oblong producer shaft with two opposite long and two opposite short side walls, an oblong distillation conduit on top of the said producer shaft and of corresponding shape for supplying residue of distillation to the same, a perforated long side wall of the said conduit, means for heating a long side wall of the said conduit, and a canal communicating through the said perforated long side wall with the said conduit for discharging generated distillates.
14. In a gas producer, a distillation conduit, two chambers, a heating chamber and a steam-chamber partly inclosing said conduit, a source of combustible communicating with said heating chamber, an air supply for consuming said combustible, and outlet for gaseous products of combustion from said heating chamber, a steam inlet into said steam-chamber, a steam outlet from said steam-chamber into said conduit, and a heat conducting wall between the two said chambers for transferring heat from said heating to said steam chamber.
15. In a gas producer, a combustion chamber, a distillation conduit, a double metal sidewall of said conduit, a plurality of heating chambers within said double metal wall and each constructed to keep its contents separate from the contents of any other of said chambers and to convey heat through a metal wall to fuel in said conduit, and a plurality of outlets for gaseous products from said combustion chamber and each communicating with one of said heating chambers.
16. In a gas producer, an oblong producer shaft with two opposite long and two opposite short side-walls, an oblong distillation conduit on top of the said producer shaft and of corresponding shape for supplying residue of distillation to the same, perforations in each of the two long walls of the said conduit, means for heating the two long walls of the said conduit, and a plurality of canals communicating through the said perforations with the said conduit.
17. In a gas-producer, a combustion-chamber, a retort, a double wall on each of two opposite sides of the said retort, two sets of compartments within the said double-wall, one of the said two sets communicating with the said combustion-chamber for transferring heat to the said retort, and the other of the said two sets communicating with the said retort.
18. In a gas-producer, a combustion-chamber, a retort, a double-side-wall of the said retort, two sets of compartments within the said double-side-wall, one of the said two sets communicating with the said combustion-chamber for transferring heat to the said retort, and the other of the said two sets communicating with the said retort for delivering thereto a fluid not containing a substantial quantity of free oxygen.
19. In a gas-producer, a combustion-chamber, a retort, a double-side-wall of the said retort, two sets of compartments within the said double-side-wall, one set communicating with the said combustion-chamber for transferring heat to the said retort, and the other set communicating with the said retort for discharging distillates therefrom.
20. In a gas-producer, a combustion-chamber, a retort, two opposite short side-walls and two opposite long double side-walls surrounding the said retort, the interior of which in its two vertical cross-sections through the said two short side-walls and through the said two long double-side-walls having substantially the shape of a rectangle and of a trapeze respectively.
21. In a gas producer, an oblong retort for distilling solid fuel and having two opposite short and two opposite long sides in a horizontal cross-section, an oblong heating chamber substantially parallel to one long side of the said retort and separated from the interior thereof by a substantially straight, long metal wall, a substantially horizontal conduit for a fluid of moderate temperature past the greater part or the whole length of the producer and substantially parallel to the said retort and partly inclosed by a part of the said long metal wall, means for supplying a heating agent into the said heating chamber, and an upper and a lower outlet for distillates from the opposite long side of the said retort.
22. In a gas producer, a down-draft combustion chamber, an air-inlet into said chamber, a plurality of gas outlets from said chamber and below said inlet, a distillation conduit anterior of said chamber but communicating therewith, and a plurality of gas discharge-canals within the wall of said chamber and each extending past said conduit and partly inclosed by a heat conducting wall constructed to be in contact on one of two opposite sides thereof with hot gaseous contents discharged through one of said

outlets and on the other of said sides with solid fuel in said conduit, but to keep separate said gaseous contents from said fuel.

23. In a gas producer, a combustion chamber, a distillation conduit, two heating chambers each constructed to heat and to distil fuel in said conduit and to keep its gaseous contents separate from the gaseous contents of the other of said heating chambers, a

10 canal for the supply of a gaseous heating agent and located outside of said gas producer, a separate inlet into and a separate outlet out of each of said heating chambers, the inlet into one of said heating chambers, 15 communicating with said combustion chamber, and the inlet into the other of said heating chambers connected to said canal.

24. In a gas producer, a combustion chamber, a distillation conduit, two heating chambers each constructed to keep its gaseous contents separate from the gaseous contents of the other of said heating chambers and to heat and distil fuel in said conduit, a separate inlet into and a separate outlet out of 20 each of said heating chambers, and each said separate inlet operatively connected to said combustion chamber.

25. In a gas producer, a source of combustible gas, a distillation conduit, a first 30 heating chamber in communication with said source and extending past said conduit for heating fuel therein, a second heating chamber constructed to heat fuel in said conduit and to keep separate its contents 35 from gaseous contents in said first heating chamber, an inlet for fluid from the outside of said gas-producer into said second heating chamber, and a perforated wall connecting said second heating chamber to said 40 conduit.

26. In a gas producer, a down-draft gas generating chamber, an air-inlet communicating with the upper part of said chamber, a gas outlet from a lower part of said chamber, a distillation conduit anterior of said chamber and constructed to convey, heat and distil fuel and to deliver residue of distillation into said chamber, a metal wall of said conduit and constructed to surround 45 fuel conveyed therein and to be in contact with the surrounded fuel by means of its inner surface, and means for leading hot gaseous products of combustion into contact with the outer surface of said wall on oppo-

site sides of said conduit for heating fuel 55 in contact with said inner surface on said opposite sides.

27. In a gas producer, a producer shaft, an upper and a lower air inlet into and an intermediate gas outlet out of said producer shaft, a distillation conduit anterior of said producershaft and constructed to deliver residue of distillation into the upper part thereof through an outlet for residue, means for heating said conduit and fuel therein, a 60 separate outlet for distillates from said conduit, an inlet for distillates into said producer shaft and intermediate between said upper and said lower air inlet, a canal connecting said outlet for distillates to said inlet for same, and a wall between said upper and said lower air inlet and constructed so as to prevent said distillates coming into contact with and being consumed by a consequential amount of free oxygen from the 65 atmosphere during their passage from said inlet for distillates through the fuel bed in said producershaft toward said gas outlet.

28. In a gas producer, a producer shaft, an upper and a lower air inlet into and an intermediate gas outlet out of said producer shaft, a distillation conduit anterior of said producer shaft and constructed to deliver residue of distillation past an outlet for same into the upper part of said producer shaft, means for heating said conduit and fuel therein, a plurality of separate outlets for distillates from said conduit, a plurality of inlets for distillates into said producer shaft and each intermediate between said 80 upper and said lower air inlet, a plurality of canals each connecting one of said outlets for distillates to one of said inlets for same, and a wall between said upper and said lower air inlet and constructed so as to 85 prevent said distillates coming into contact with and being consumed by a consequential amount of free oxygen from the atmosphere in passing from said inlets for distillates through the fuel bed in said producershaft 90 toward said gas-outlet.

In testimony whereof I have signed my name to this specification in the presence of two subscribing witnesses.

HENNING FRIEDRICH WALLMANN.
